United States Patent Office.

JOHN B. BRACKETT AND WYMAN DEARBORN, OF BOSTON, MASSACHUSETTS.

Letters Patent No. 63,186, dated March 26, 1867.

IMPROVEMENT IN COTTON GINS.

The Schedule referred to in these Letters Patent and making part of the same.

TO ALL WHOM IT MAY CONCERN:

Be it known that we, JOHN B. BRACKETT and WYMAN DEARBORN, of Boston, in the county of Suffolk, and State of Massachusetts, have invented a new and useful Improved Cotton Gin; and we do hereby declare that the following is a full, clear, and exact description of the construction and operation of the same, reference being had to the accompanying drawings, forming a part of this specification.

Figure 1 is a side elevation, which is a side elevation having the interior construction dotted through.

A is the side or frame of the machine, pierced with holes and slots as drawn; B is the feeding platform; C C' are rolls, enveloped by the endless belt D, which is drawn and represented as of rubber, but may be of rubber and cloth, or even of an even quality of heavy web. Between the two rolls, there presses upon the outside of the endless belt E, a fixed pressure-bar convex toward the belt, flat on the side away from the belt, and thin at the top and in front of the pressure-bar vibrates the clearer, F, shaped and arranged as drawn, and hung to levers, G, placed above the rolls C C'. These levers are formed with a slotted end, g, in which revolves the crank of cranked rod H, giving a reciprocating motion to the clearer. Rod H is operated by an endless belt from roll C. Any degree of tension may be given to belt D by means of levers j, the location and operation of which can be controlled by shifting the fulcra of levers k among the notches or pegs e e'. The roller C' has a journal passing into a movable bearing, J, which plays vertically in the slot of the frame, and to which the levers j are attached by any suitable means. A parallel motion is secured to clearer F by means of rods, m, connecting it with the feeding platform B. Additional tension may be given to the belt D by means of a tightening roll forced against the belt, as shown at p, or by other proper means. Cotton is fed to the machine while in motion, passes between the endless belt D and pressure-bar E, and the seed is doffed off by clearer F, and falls outside of apron or guard N, while the fibre passes inside of the same. The speed and action of the machine are regulated with great ease by means of the tightening apparatus and endless belt D, and the belt, in combination with the convex pressure-bar, presents a far more perfect device for cleaning the cotton from seed than the concave pressure-bar and elastic roll now in use in other gins. The clogging of the connections of the clearer, also, is avoided by hanging it above the rolls, and its certainty of action is insured by avoiding long connecting-rods and by bringing the power close to the work. Of course the notches e e' may be replaced by holes and pins and serve for fulcra equally well.

We claim as our invention, and desire to secure by Letters Patent—

1. The rolls C C', constructed as described, as arranged with the belt D, in combination with the sliding bearing J, and levers j, with their variable fulcra, substantially as and for the purpose described.
2. The rolls C C', constructed as described, in combination with the convex pressure-bar E, and endless belt D, arranged and operating as and for the purpose described.
3. The arrangement of pressure-roll in combination with belt D, when arranged as described, in connection with rollers C C', and pressure-bar E, as and for the purpose described.
4. The arrangement of slotted levers G, in combination with clearer F, and crank-shaft H, and the further combination of said clearer, levers, and crank-shaft with rods m, as and for the purpose described.

JOHN B. BRACKETT,
WYMAN DEARBORN.
